WINDOW SHADE

William B. Galley, Eagle Rock, Calif.

Application October 21, 1935, Serial No. 45,923

6 Claims. (Cl. 156—16)

This invention relates to shades for windows comprising a plurality of strips or splints adapted by their relative association and movement to obstruct the passage of light therethrough.

5 Shades of the Venetian or folding-split type have heretofore been inapplicable for use on small windows, principally because of the apparatus and rigging necessary for their operation, which is excessively expensive in consideration of 10 the advantages derived therefrom, and often detracts from the appearance of an otherwise well-appointed room. Difficulties in operation resulting from numerous ropes, pulleys and the like, or loose association of the parts have further 15 militated against their universal application.

A general object of the present invention is to avoid the difficulties of the prior art by the provision of a window blind comprising a plurality of splints having their edges associated to form a 20 compressible plait, in which the extension of the plait is determined by the vertical position of a manually vertically-adjustable bottom splint.

A specific object hereof is to provide a pair of 25 guide wires or rods secured relative to the window so as to determine the alignment with the window of all of a plurality of splints comprising a blind and prevent displacement of the same by wind or other force tending to fracture the splints, or mar the finish or painted surface of the 30 adjacent window frame.

Another object of my invention is the provision 35 of a blind embodying a frictional clamping means adjacent a lower bar adapted to maintain the blind in any adjusted position.

Still another object is to provide a device embodying compactness, economy of manufacture, 40 ease of operation, installation and removal, as well as simplicity in construction and appearance, which facilitates its design and ornamentation for conformance to specific architectural themes.

Fig. 1 is a perspective view of my invention operatively installed over the inside of a window frame.

Fig. 2 is a sectional view on line 2—2 of Fig. 1. 45 Fig. 3 is a section on line 3—3 of Fig. 2.

Fig. 4 is a view on line 4—4 of Fig. 2.

Referring more particularly to the drawing, the numerals of which designate similar parts throughout the several views, 5 indicates a plurality of splints, preferably of wood, although metal or other materials may be used in specific embodiments. The opposite longitudinal edges of splints 5 are secured together by means of a cord 6, the ends of which extend upwardly around 50 the lowermost splint near one end thereof, and

are oppositely interlaced with the upper splints forming the body of the blind, that is to say, the opposite ends of the cord are crossed above each splint and travel upwardly on opposite sides of the splints so as to maintain the edges of the 5 splints together. The ends of the cord 6 are secured adjacent the top splint 5a by means hereinafter described. A second cord 7 is similarly woven near the opposite ends of the splints. The flexibility of the cords 6 and 7 effects a hinge 10 between the splints, forming by relative angular movement therebetween a variable accordion plait.

The uppermost splint 5a is reinforced by strips 8 fastened to opposite sides of the splint by nails, 15 screws, or the like, thus securing the upper ends of cords 6 and 7. The top bar 9 of the shade, comprising splint 5a and strips 8 is secured rigidly to the top rail 10 of a window frame by screws 11. The bottom splint 5b is also reinforced by 20 strips 12 attached by any well known means, such as by nails, to opposite sides thereof.

A pair of rods or wires 13 having their upper ends clamped between strips 8 and splint 5a protrude from the top of bar 9 and thence extend 25 downwardly on the outside thereof. Each strip, except those in the upper and lower bars, is provided with a hole 14 near each of its ends through which rods or wires 13 are threaded. A pair of studs 15 mounted in respective brackets 30 16 are secured by screws 17, or the like, to the bottom of opposite jambs 18 of the window frame. The lower ends of wires 13 extend through holes 19 provided in respective studs 15 and in vertical alignment with the point in bar 9 at which the 35 wires are fastened. The wires 13, drawn taut between bar 9 and their respective studs 15, are prevented from loosening or being withdrawn from holes 19 by having their ends wound around the stud and inserted in a second hole 20 provided in the studs 15 adjacent each of holes 19, as illustrated clearly in Fig. 4. Each splint is thus slidable on wires 13. Due to the tautness of the wires, the minimum angle which the splints will assume relative to the vertical is determined 45 by the size of the holes 14 in the splints which engage with wires 15 when the splints are stretched thereon.

By employing an uneven number of splints the upper and lower bars may be disposed on 50 opposite sides of wires 13, as illustrated. Thus with the upper bar secured to the top rail 10 of the window frame, inside of wires 13 as above noted, the lower bar comprised of strips 12 and splint 5b will be located on the outside of the 55

outside of the wires, for a purpose about to be described: A pair of U-shaped clamps 21 to associate the lower bar with the wires, are secured at the back of the lower bar, one adjacent each 5 wire, by a screw 22. Each clamp is arranged with its two parallel portions 23 and 24 perpendicular to its respective wire 13 which extends therebetween. The friction of the clamps on the wire is regulated by means of a screw-headed 10 stove bolt 25 which extends from the outside of the lower bar through the bar and a hole 26 in the adjacent portion 23 of the clamp, being tapped into the opposite portion 24. The rotation of the bolts 25 regulates the relative proximity of the 15 portions 23 and 24 of each clamp which grip the wire and offset the force of gravity on the lower bar and the splints supported thereon.

It will thus be seen that I have provided a blind in which a plurality of splints relatively hinged 20 by means of cords have incorporated therewith wires or rods adapted to perform a double function, i. e., of sustaining the splints so associated in a variable accordion plait; and to further maintain the blind in rigid alignment with the 25 window. The frictional contact of the clamp 21 with the wires, being only great enough to support the weight of the splints, is easily offset by manual movement of the lower bar to thus easily and quickly lower the shade over the window to 30 the position desired, where it will be retained.

While I have illustrated and described but one embodiment of my invention, it will be obvious to those of skill in this art that wires 13 may be substituted by tubing or rods of any material 35 embodying sufficient inherent rigidity to resist the frictional wear of the clamping member; and that various other changes may be made, as, for instance, in the number of the cords and wires, in the relative arrangement of the wires with respect to the ends or sides of the splints, in the 40 means for securing the ends of the cords and wires, as well as in the design, proportion, number or arrangement of any of the parts hereof, without departing from the spirit of my invention.

Having described my invention, I claim:

1. In a window shade, a plurality of splints having their longitudinal edges hinged together to form an accordion plait, each of said splints having a hole therein, a guide secured perpen-

dicularly to the longitudinal axis of one of said splints extending through holes in the other of said splints, and clamping means secured to one of said splints to frictionally engage said guide.

2. A window shade comprising a plurality of 5 relatively hinged splints, a guide secured to one of said splints to maintain the remaining splints in alignment therewith, and clamping means secured to one of said splints to frictionally engage said guide.

3. In a window shade, a plurality of splints each having a hole therein, cords interlaced with said splints to maintain longitudinal edges of said splints relatively adjacent, a bar secured parallel to the longitudinal axis of one of said splints, a 15 guide secured perpendicularly to said bar and extending through holes in said splints, and clamping means secured to one of said splints to frictionally engage said guide.

4. In a window shade, a bar adapted to be supported by a plurality of splints, a strip of resilient material bent to form a U-shaped clamping member, means to secure said clamping member to said bar, and means to regulate the relative proximity of the sides of said member.

5. In a window shade, a plurality of splints each having a hole therein, cords interlaced with said splints so as to hinge the longitudinal edges of said splints together, forming an accordion plait, bars secured to each end of said plaited 30 splints, a guide perpendicularly secured relative to one of said bars and extending through a hole in each splint, and an adjustable clamp secured to the other of said bars to frictionally engage the guide.

6. In a window shade, a plurality of splints each having a hole therein, cords interlaced with said splints so as to hinge the longitudinal edges of said splints together, forming an accordion plait, bars secured to each end of said plaited 40 splints, a guide perpendicularly secured relative to one of said bars and extending through a hole in each splint, a strip of resilient material bent to form a U-shaped clamping member, means to secure said clamping member to said bar, and 45 means to regulate the relative proximity of the sides of said member.

WILLIAM B. GALLEY.
